ROTATABLE DISK, PERPETUAL CALENDAR
WITH INTERLACED SPIRAL FORMATIONS

Richard Blodget, Chicago, Ill.

Application February 15, 1945, Serial No. 577,989

2 Claims. (Cl. 40—113)

1

My invention relates to certain new and useful improvements, and developments in the calendar art having specific reference to perpetual type of calendars, which aim to provide a simple and effective means of indicating the monthly calendar for any month of years, past, present or future, in both the Julian as well as the Gregorian system of computation, giving the correct monthly calendar for months of "28," "29," "30" or "31" day length of any year forever starting with the year one A. D.

An important object of my invention is to provide an article of the aforementioned character which is comprised of a static or stationary support section upon which is rotatably mounted a dial; an object of my invention being to provide, by one simple adjustment, in addition to a preliminary computation in accordance with a table furnished with my invention, thus representing a truly devised computing arrangement which indicates perpetually the calendar dates of months of "28," "29," "30" and "31" day length, for years as well as for leap years.

Another important object of my invention is to provide, in connection with the structure for determining the calendar dates, a numerically arranged table which segregates the years into centuries, decades, and unit years, so that the three may be correlated to give any particular year desired, and thus furnish a table requiring minimum of space, arranged for the greatest convenience and completeness, and showing by a simple formula the centuries repeating in sequence. Starting with the century digits, or the Julian or Gregorian index for the century digits, the sequence is horizontally across a row to the decades digits, or tens digits, and thence perpendicularly down a column to the year, or units digit, and subsequently horizontally across a row to the intersection of the said units row with the months column, where will be found the number referring to the calendar number for the month of which there are "28" in number thus furnishing a complete number of combinations and permutations of the seven days of the week with the four lengths of months, such as, namely, months of "28," "29," "30" and "31" day duration.

Another object of my invention is to provide a grill which encompasses substantially a semi-circular magnitude, and in which are a series of trapezoidal openings which are sufficiently spaced apart so that the intermediate spaces between the trapezoidal openings will conceal an adjacent calendar.

2

Another object of my invention is to provide a key opening or index register with which is brought into alignment the numeral representing the Gregorian or Julian index imprinted on a circular dial, the same having first been obtained from the table and computation from the formulas indicated on a portion of the table, and so used in conjunction with the table, to determine the arrangement of days of that particular month for the particular year which it is sought to establish.

An important feature of my invention is to provide a dial which is continuously numbered repeating each of the numbers twice, the numbers being repeated twice beginning with one, and arranged in two intertwined spiral formations so that one spiral is positioned with respect to the other spiral a lead of 180°. The distinguishing feature between the two spirals is that the primary spiral begins with one, and the dates are repeated twice and terminates with the number "29" which appears but once, then a space is provided and the numeral "30" appears once, that being distinguished from the secondary interlacing spiral numerical arrangement, which is identically the same, with the exception that it terminates with the numeral "29" being repeated twice, and adjacent thereto, the numeral "30" appears once, then a space between the numeral "30" and the last numeral "31"; the said dial is also numerically designated with index numbers beginning with one and continuing in rotation, the one commencing under the second weekly arrangement beginning with the column "4," "11," "18," "25" and being thence consecutively numbered until the ultimate index "28" is reached.

Another feature of my invention is to provide a support of easel-like formation which is collapsible and may be set up flat for transit purposes and mailing, and also which is provided with tab locking means so as to permit rigid triangulation of the support proper resembling an easel structure whereby the article or calendar may be conveniently positioned on a table or desk and conveniently manipulated when it is desired to indicate thereon any particular calendar or date.

Another object of my invention is to provide an article of the aforementioned character which is practical in construction, useful and efficient for the purposes for which it has been created, and of such simple elemental structure as to warrant economical production thereof in quantity.

Other objects, features, and ancillary advantages reside in certain novel features of construction, arrangement and combination of parts which will be hereinafter more fully described, and particularly pointed out in the appended claims, reference being had to the accompanying drawings forming a part of this specification, in which like symbols are used to designate like parts, and in which:

Fig. 1 represents a front perspective of my invention.

Fig. 2 is a longitudinal cross-sectional view thereof.

Fig. 3 is a rear perspective view pointing out other features of my invention.

Fig. 4 represents the numerical arrangement of the dual spiral formation of calendar weeks depicted on the dial in order to enable deduction of calendar dates in conjunction with the use of the preliminary calculation from the algebraic formulae and tables provided therefore.

Fig. 5 is a blank or development of the easel structure comprising one element of my invention.

Referring to the various figures, 6, generally, designates my invention which is made up of one blank (as indicated in Figure 5) consisting of a front portion 7, a rear portion 8, and a lock portion 14 for locking and securing the three portions in triangular or easel formation. The blank is cut out to the approximate shape indicated in Figure 5, and is provided with weakened line portions 41 and 40 to facilitate bending the same so as to assemble as indicated in Figure 1. The blank is also cut out at 11 and 10, so that when the same is folded over to provide a clearance opening permitting the edge of the rotatable dial 12 to be manipulated by the thumb or fingers, the said dial being secured by having its central opening 31 secured to the opening 42 by virtue of a grommet 27 which holds the same in assemblage frictionally and movably, maintaining the dial 12 under slight frictional engagement with respect to the front portion 7 of the structure, generally, designated 6. The blank is further recessed in grill-like formation encompassing approximately a semi-circular area 25, the grill openings 19 being of a trapezoidal shape, though one of the said trapezoidal openings designated 20 is provided with a small calendar index register opening at its base designated 21, the purpose of which is to be hereinafter more clearly elucidated. It should be noted that the said trapezoidal openings are evenly spaced by intermediate areas or portions.

The rear portion 8 of the blank has an enlarged slotted portion 17 merging with a reduced slotted portion 18 and is also cut out as indicated at 9 in order to facilitate rotating the dial 12 by frictional contact of the fingers with its edge, in the event that the structure is hung up on a wall by means of the hanging openings 22 when the easel retaining portion 14 is not locked in engagement with the slotted portions 17 and 18. When set up in easel formation as indicated in Figure 1, the locking tab portion 15 being spaced from the portion 14 by virtue of locking slot 16, permits the tab 15 to enter the slot 17 until the reduced neck portion 16 is in alignment with the side edges 43 of the reduced slot 18 whence the tab 15 is brought down into locking engagement so that the side walls 43 thereof are engaging the slotted portion, or reduced neck portion 16, as more clearly indicated in Figure 3.

Referring to Figure 4, the dial structure which is deemed an important element of my invention is indicated in detail, and it comprises, a circular disc designated 12 of suitable diameter having a securing hole at its mid point designated 31 and having imprinted thereon a series of numerals in spiral formation arranged consecutively from "1" to "30" on one spiral formation designated 29, and another spiral formation enumerated from "1" to "31," the two spiral enumerations being interwoven and staggered by a differential lead of 180° at the starting point of each spiral formation.

The distinguishing features between these two spirals are that in one case the numerals are duplicated, that is "1" "1," "2" "2," "3" "3," etc., until the numeral "29" is reached which is not repeated, but a blank space is left after the numeral "29" appearing but once, and after the blank space the numeral "30" terminates that spiral enumeration; the other spiral arrangement duplicates the numeral "29" but only indicates the numeral "30" once with an intermediate blank space and then terminates with the numeral "31" indicated only once. The said interlaced spiral arrangement provides a series of weekly calendar dates for the different days of the week and are numbered for further purposes to be hereinafter more clearly elucidated, from "1" to "28," respectively, the said enumeration being designated 30.

On the front portion 7 of the calendar, I indicate the semi-circular area 25 within which is confined the grill section, hereinbefore, referred to and having the slots or the openings 19 and 20, also having at the top thereof a legendary indication of the days of the week, generally, indicated 26, and the weekly dates that happen to coincide or register at the instant positioning of the dial 12, under the calendar index "8."

In this particular calendar, "8" indicates its numerical index characterized by the numeral 30 showing the dates of the week designated in columns 36. All this material is imprinted on the lower section 23 of the calendar portion 7; the upper section 24 thereof indicating a number of tables and algebraic formulae for preliminary computation used in connection with the determination of certain calendar numbers or indices. The upper section 24 is sub-divided into a section 32 which contains a series of calendar numbers falling in each of seven categories designated by the letters *a, b, c, d, e, f, g*, above which the calendar months are indicated as January, February, March, April, May, June, July, August, September, October, November, and December indicating the respective days therein, and in the months of January and February two columns are indicated in order to take care of the leap years which have a bearing on the calculation and determination for obtaining the proper calendar indices 30. Above the month arrangement there is a section on which, for handy reference, is provided and designated 34, the algebraic formulae for preliminary calculation and determination of the Julian index, or the Gregorian index; the said formulae may be utilized for converting from the Julian index to the Gregorian index various calendar dates. Adjacent to the section 33 and to the left thereof, I indicate the columns 36 and 35; the column 36 indicating the century digits for four Gregorian centuries, namely, 1700, 1800, 1900 and 2000; whereas the column 35 indicates the Julian and Gregorian index for all centuries as deter-

mined by formulae 34. Immediately to the left of the columns 35 and 36 and adjacent or contiguous thereto, I have tabulated the decade table 37, and directly below the same the table 38 the unit or year table. On the table in section 32 one column for January is indicated in red, and one column in February is also indicated in red, while on the unit or year table 38 various numerals are indicated in red, the said numerals indicating leap years and when in the determination of a certain calendar index the unit numeral happens to be a red numeral, the numerals aligned in the red column under January and February are to be used as calendar indices.

Since the Gregorian calendar was adopted on September 14, 1752 the arrangement on my table indicates from the seventeenth century on the computation of Gregorian calendars. The use of my calendar for Gregorian years beginning with the seventeenth century is as follows: Example: November 11th, 1918 the first Armistice day. Now to locate the proper calendar index under the Gregorian system of notation, we first locate the century digits "19" above the column of letters *a*, *b*, *c*, etc., and proceed to the left section 37, until the decade digit one is reached, this column is followed down into section 38 to the year digit "8;" once that is done the next procedure is to move to the right of the digit "8," thus located, to section 32, and at the intersection of this row and the month column, namely, November the calendar number "28" is found; the dial is then rotated until the number "28" appears in registry or coincidence with the opening 21, and the proper calendar is thus set, whence it can be seen that November 11th, 1918 fell on a Monday.

In leap years, the red numbers under January and February are used. If the year digit is red, it indicates a leap year, excepting for those century years in the Gregorian system not divisible by four hundred such as 1700, 1800, 1900, 2100, etc.

In the Julian calendar, which preceded the Gregorian calendar, every year divisible by four is a leap year without the above exception. The letter to the right of the year digit is the Sunday letter, in leap years it applies only to the last ten months. For all Julian years the computation is as follows: Add the numeral "2" to the century digits and divide by "7;" for all Gregorian years take two times the century digits and divide by "8," in either case locate the remainder left after factoring out the divisor and proceed further as follows: Example: October 12th, 1492 Julian calendar "14" plus "2" equals "16;" "16" divided by "7" equals "2" and "2" remainder; locate the remainder "2" called the Julian index above the column of letters *a*, *b*, *c*, etc., and proceed to the left until the decade digit "9" is reached in section 37; follow this column down into section 38 to the year digit "2," now move to the right to section 32, and at the intersection of this row and the month October is the calendar number or index "8," turn the dial until this number "8" appears in registry with opening 21 and you will have the calendar desired October 12th, 1492 Julian calendar fell on a Friday. This example is depicted and illustrated in the setting of Figure 1.

Another illustration is, for example, using the conversion system from the Julian to the Gregorian calendar; George Washington was born Friday, February 11th, 1732 and according to the Julian formula the remainder is "5," and

the calendar index is "7," whereas according to the Gregorian calendar that date is found in calendar "1" and is February 22nd, 1732.

Another use for my invention is for finding when a certain date will fall on a certain day. Example: When next will July 4th fall on Wednesday? Starting with the smallest calendar number under July which is "2" (see section 32), set the dial at each in turn until the 4th is under 10 Wednesday. The calendar index then showing will be "10." The row containing calendar number "10" under July will also contain the year digit for all years having the 4th of July on Wednesday. Thus we see that 1934 was the last, and 1945 the next year with July 4th on Wednesday. For January and February, this process must be repeated once for each column to find the next regular year and the next leap year that answers the problem.

It should be noted that the algebraic formulae for the Julian and Gregorian calendar indices are equivalent tho not equal since they represent the same period of time in the existence of the universe, the notation or designation of the said period of time merely differing according to its designation whether Julian or Gregorian. The numerals covered with perpendicular section lines designate black letters on a red background or red letters may be imprinted. These red imprints are used for computations involving the leap year.

I believe I have illustrated rather clearly, and described rather succinctly the nature of the construction and use of my invention, but it is readily obvious that changes may be made therein within the spirit and scope of the disclosure, and I reserve the right to any such changes as well as those that fall within the embodiment of the accompanying drawings, also those falling within the purview of the foregoing description.

Having thus described and revealed my invention, what I claim as novel, and desire to secure by Letters Patent, is:

1. A perpetual calendar comprising, a static support having a grilled section, a computing section, and a calendar index register merging with an opening of the said grilled section; and a calendar dial rotatably mounted on the said static support, the said dial having imprinted thereon the numerical days of the month arranged in dual interlaced spiral formations and spaced initially with a starting lead of 180° seven alternate columnar portions thereof being exposed simultaneously through the said grilled section, the composite interlacing of the said spiral formations resulting in 28 calendar indices, each of the said indices adapted to be exposed alternately through the said calendar index register, the said numerical days of the month being imprinted twice only up to and including the numeral 28 but all of the numerical days being consecutively arranged for each of said spiral formations, one of said spiral formations terminating with the numeral 30 in which the numeral 29 appears once, the other of said spiral formations terminating with the numeral 31 in which the numeral 29 appears twice and the numeral 30 appears once, the numerals 30 of said one spiral and 31 of said other spiral formation appearing but once in each of said spiral formations and being preceded by a blank space.

2. A perpetual calendar comprising, a static support having a grilled section, a computing section, and a calendar index register merging with an opening of said grilled section; and a

7
 calendar dial rotatably mounted on the said static support, the said dial having imprinted thereon the numerical days of the month arranged in dual interlaced spiral formations and spaced initially with a starting lead of 180° exposed through the said grilled section, the composite interlacing of the said spiral formations resulting in 28 calendar indices, each of the said indices adapted to be exposed alternately through the said calendar index register, the said composite interlacing of the said spiral formations registering alternate columns of dates with the openings in the said grilled section, the said numerical days of the month being imprinted twice only up to and including the numeral 28 but all of the numerical days being consecutively arranged for each of said spiral formations, one of said spiral formations terminating with the numeral 30 in which the numeral 29 appears once, the other of said spiral formations terminating with the numeral 31 in which the numeral 29 appears twice and the numeral 30 appears once, the numerals 30 of said one spiral and 31 of said other spiral formation appearing but once in each of said spiral formations and being preceded by a blank space.

25
 RICHARD BLODGET.
